UNITED STATES PATENT OFFICE.

RALPH S. BARRETT, OF INDIANAPOLIS, INDIANA, ASSIGNOR TO LEO M. BARRETT, OF INDIANAPOLIS, INDIANA.

WRENCH.

No. 902,799.

Specification of Letters Patent.

Patented Nov. 3, 1908.

Application filed July 17, 1908. Serial No. 443,980.

To all whom it may concern:

Be it known that I, RALPH S. BARRETT, a citizen of the United States, residing at Indianapolis, in the county of Marion and State of Indiana, have invented certain new and useful Improvements in Adjustable Wrench Handles; and I do declare the following to be a full, clear, and exact description of the invention, reference being had to the accompanying drawings, and to the letters and figures of reference marked thereon, which form a part of this specification.

This invention relates to the well known type of wrenches commonly named "monkey" wrench, and has reference particularly to built-up handles thereof, and especially to the external portions of the handles.

The object of the invention primarily is to provide improved handle frames that will be adapted to be formed of cast metal such as steel or malleable-iron in a cheap manner; a further object being to provide an improved handle frame that will be adapted to have simple and cheap forms of wooden or other filling pieces connected thereto, a still further object being to provide improvements in wrench handles whereby they may be made inexpensively, and be very strong and convenient to handle, and durable in use, and adapted to prevent in a great measure injury to the filling pieces when the wrenches are placed on work benches or floors, or elsewhere.

With the above mentioned and other objects in view the invention consists in an improved wrench handle having certain novel features of construction, and consisting further in the parts, and combinations and arrangements of parts, as hereinafter particularly described and defined in the accompanying claims.

Referring to the drawings, Figure 1 is a front view of a quick acting adjustable wrench having the improved handle thereon, the wrench being shown as when placed on a plane surface, as a bench, with the undermost portions of the handle filling piece held clear of the plane surface, so that the wooden portion may not be marred by contact with the work-bench or metal chippings that might be on the bench; Fig. 2, a longitudinal sectional view on the line A—A in Fig. 1; Fig. 3, a longitudinal sectional view of the handle on the line B in Fig. 2; Fig. 4, a side elevation of the handle; Fig. 5, a

transverse sectional view on the line C—C in Fig. 2; Fig. 6, a side elevation of the handle frame; Fig. 7, a transverse sectional view on the line D—D in Fig. 4; Fig. 8, a transverse sectional view on the line E—E in Fig. 6; Fig. 9, a transverse sectional view on the line F—F in Fig. 4; Fig. 10, a longitudinal sectional view on the line G—G in Fig. 6; Fig. 11, a plan of the inner side of either one of the filling pieces of the handle; and Fig. 12, a perspective view of the handle frame. H—H indicates the plane on which the wrench will normally lie when placed on its side.

Similar reference characters throughout the drawings indicate corresponding elements or features of construction referred to herein.

In the drawings the numeral 1 indicates the body part forming a part of a lever and having a fixed jaw 2 on one end thereof, a movable jaw 3 being mounted slidingly on the body part and having an extension 4 formed therewith in which are screw-threads 5, all formed in the usual manner, the body part having a shallow groove 6 in a side thereof that is adjacent to the extension. The handle is formed partially by the portion 7 of the body part which has two tapering portions 8 and 8' from which extends a relatively thin shank 9 also forming a part of the lever and the handle, the shank being of the same width as the body part and having beveled sides 10 and 10' at the end portion 9' of the shank, the end 9" of the shank being squared.

The principal part of the improved handle is cast in a single piece, preferably of steel, and constitutes a frame having a collar 11 in which is an opening 11' to receive the handle portion 7, two opposite sides of the collar having rivet holes 12 and 12' therein receiving a rivet 13 that extends through the handle portion 7 on which the collar is rigidly secured by the rivet, the collar serving to strengthen the handle portion 7. The collar has an abutment 14 formed on one side thereof in which screw-threads 15 are formed. A double ended screw is provided having continuous threads 16 on one end thereof engaging the threads 15 and oppositely pitched threads 17 engaging the threads 5 in the extension 4 of the movable jaw, the screw having an enlargement at the middle of its length formed as a knurled turning wheel 18

for operating the screw by hand, the turning wheel traveling in the groove 6 when in operation. The collar 11 has a casing 19 formed on one side thereof that extends 5 from the abutment 14 and has an end 19' opposite to the inner end of the screw that works in the abutment 14. The two longer sides of the collar 11 have external flanges 20 and 20' formed thereon at the end thereof 10 that is toward the jaws of the wrench to serve as supports for holding the handle of the wrench clear of any surface upon which the wrench may be placed on either one of two of its sides, there being also a reinforcing 15 flange 21 on the end of the collar and joined to the flanges 20 and 20'. Two bars 22 and 23 extend from the end 24 of the collar 11 along the opposite narrower sides of the shank part 9, the inner sides 22' and 23' being 20 straight and parallel one to the other and in the planes of the narrower sides of the oblong aperture 11'. The end 24 has a square face and the bars 22 and 23 have relatively broad portions where they join the collar 11 that 25 have inclined sides 25 and 25'. A cap 26 is formed on the ends of the bars and has two grooves formed in opposite sides thereof having bottoms 27 and 27' that extend from the planes of the inner sides of the bars convergently to the inner side of the end of the cap, the cap having a squared inner end 28 that is parallel to the squared face 24 of the collar, and the other two sides of the cap have internal recesses 29 and 29' so as to simplify 30 the work of fitting the cap to the end portion 9' of the shank, the grooves receiving the tapering sides 10 and 10' thereof, the inner side of said cap at the sides of the grooves having walls 30 and 30' and 31 and 31' that 35 engage the broader sides of the end portion 9' adjacent to the tapering sides 10 and 10'. This construction enables the cap and the shank portion to be readily fitted together closely so that rigid connections may be 40 formed to withstand the shocks incident to rough handling of the wrench when throwing it about during use. The cap has two extensions 32 and 32' extending from the inner end 28 along opposite sides of the bar 22 and 45 also two other extensions 33 and 33' extending from the end 28 along opposite sides of the bar 23. The extensions 32 and 33 have divergent inner sides 34 and 34' respectively that are straight and stand up at right angles 50 to the side faces of the bars 22 and 23, said extensions projecting inward beyond the inner sides 22' and 23' of the bars at their bases or junctions with the cap. The other two extensions 32' and 33' have also divergent 55 inner sides 35 and 35' corresponding to those above described.

In order to fill out the handle to make it convenient for grasping in the hand and of a suitable size, two filling pieces 36 and 36' are 60 provided of simplified form, so that they may

be cheaply fitted and made of either wood, vulcanized fiber, or other suitable material, and are both alike, each filling piece having a squared end 37 that engages the end 24 of the collar 11 and rests on one side of the shank portion 9 of the handle, the inner side of the filling piece being flat and having recesses 38 and 38' to receive the inclined parts 25 and 25' of the bars 22 and 23, the filling piece having an opposite squared end 39 engaging the end 28 of the cap and having also two tapering sides 40 and 40' that engage the inner sides of two extensions of the cap, so that the filling pieces rest on opposite sides of the shank portion 9 and also on the sides of the bars 22 and 23 and are prevented from all sliding movements, each filling piece having a rivet hole 41 in its middle portion receiving a rivet 42 that extends through the shank portion 9 and secures both filling pieces 85 to their companion parts.

The wrench is used in the usual manner and when falling or when dropped onto benches or floors, will first strike the bench or floor and as usual the wrench may then fall on one of its broader sides which ordinarily would mar the filling pieces of the handle, but in the improved wrench the handle may be stopped by the flanges 20 and 20', and thus avoid injury to the more delicate substance of which the filling pieces are formed. As will be seen also the whole wrench handle is of compact and rigid construction so that no parts of the frame can yield when in use, and in the case of accident 100 sufficiently violent to break the handle frame a new frame and frame pieces may be readily substituted for those that may have been damaged.

Having thus described the invention, what 105 is claimed as new, is—

1. A wrench handle frame comprising a collar and two bars extending from the collar and having a cap formed on the ends thereof, said cap having two grooves in the inner side 110 thereof, the bottoms of the grooves beginning at the planes of the inner sides of the bars and extending convergently to the inner side of the end of the cap.

2. A wrench handle frame comprising a 115 collar, and two bars extending from the collar and having a cap formed on the ends thereof, said cap having four integral extensions projecting from the inner end thereof along the bars integrally therewith, the inner sides of 120 each two of the extensions that are on opposite bars being divergent from the cap, said cap having also two recesses therein and also two grooves between the recesses extending from the ends of the bars convergently to the 125 inner side of the end of the cap.

3. In an adjustable wrench, the combination of a body part with a movable jaw thereon and also a fixed jaw on an end thereof, a shank on the body part having a taper- 130

- ing end, a collar secured on the shank, an abutment on the collar, a screw connected with the abutment and connected also with the movable jaw, two bars extending along 5 opposite sides of the shank from the collar and having a cap formed integrally therewith that covers the end of the shank and has two grooves therein receiving the tapering end thereof, said cap having four extensions integral on the inner end thereof 10 projecting along side of the bars, the inner sides of each two of the extensions that are on opposite bars being divergent from the cap, two filling pieces having flat inner sides 15 engaging the shank and bars, each filling piece having a tapering end engaging the cap and also two opposing divergent sides of the extensions, and a securing device retaining the filling pieces against the shank.
- 20 4. In an adjustable wrench, the combination of a body part with a movable jaw thereon and also a fixed jaw on an end thereof, a shank on the body part having a tapering end, a collar secured on the shank and having 25 two flanges on opposite sides of one end there-
- of, an abutment on the collar, a screw connected with the abutment and connected also with the movable jaw, two bars extending along opposite sides of the shank from the collar and having a cap formed integrally 30 therewith that covers the end of the shank and has two grooves therein receiving the tapering end thereof, said cap having four extensions integral on the inner end thereof 35 projecting along side of the bars, the inner sides of each two of the extensions that are on opposite bars being divergent from the cap, two filling pieces having flat inner sides engaging the shank and bars, each filling piece 40 having a tapering end engaging the cap and also two opposing divergent sides of the extensions, and a securing device retaining the filling pieces against the shank.

In testimony whereof, I affix my signature in presence of two witnesses.

RALPH S. BARRETT.
